SIGNBOARD FRAME

Filed July 5, 1929

UNITED STATES PATENT OFFICE

PIERRE L. MICHAEL, OF HOUSTON, TEXAS

SIGNBOARD FRAME

Application filed July 5, 1929. Serial No. 375,905.

This invention relates to new and useful improvements in a signboard frame.

One object of the invention is to provide a frame of the character described specially designed for the mounting of out door signs, and which may be readily dismembered, without injury thereto, and when it is desired to remove the sign, and re-erected for further use.

Another object of the invention is to provide a novel type of anchoring means whereby the frame may be easily, quickly and securely anchored to the ground.

With the above and other objects in view this invention has particular relation to certain novel features of construction, arrangement of parts and use, an example of which is given in this specification and illustrated in the accompanying drawing, wherein:—

Figure 1 shows a front elevation of the device, partly broken away.

Figure 2 shows a vertical sectional view.

Figure 3 shows a fragmentary vertical sectional view taken on the line 3—3 of Figure 1.

Figure 4 shows a fragmentary side view of the anchoring means, and

Figure 5 shows a fragmentary vertical cross sectional view showing a means for anchoring the signboard to the frame.

Referring now more particularly to the drawing wherein like numerals of reference designate similar parts in each of the figures there are the end A-frames, each comprising a vertical front leg 1 and rear leg 2 diverging therefrom, the front and rear leg of each A-frame being braced by suitable braces 3, 4 as shown.

The lower ends of the legs 1, 2 are pointed so that they may be readily inserted into the ground and the upper ends of said legs 1, 2 are secured together by suitable bolts as 5. The legs 1, 2 are preferably formed of angle irons and spaced from the flanges of said legs are the clamp straps 6, 6 which are fixed with respect to the opposing leg flanges by the spaced bolts 7, 7. When the lower ends of the legs are inserted into the ground a suitable excavation is made around each leg, so as to expose the said clamp straps 6, and

anchor stakes 8 are then inserted through between the respective straps 6 and the opposing leg flanges as well as between the corresponding bolts 7 and are driven at a downwardly diverging angle into the earth and bolts 7 are then tightened up to hold said stakes 8 firmly in place and said excavations are then filled so that the anchoring means will then be entirely covered up by the earth.

The parts hereinbefore described are preferably formed of metal and are covered with a suitable protecting coating, to prevent corrosion, before being anchored into the ground. When it is desired to remove the structure, the bolts 7 may be uncovered and loosened up and the stakes 8 removed and the legs 1, 2 then readily withdrawn from the ground.

The legs 2 are secured together by the cross angle irons 9 which are transversely disposed and spaced apart and suitably secured to said legs and likewise the vertical legs 1 are secured together by the transversely arranged spaced upper and lower angle irons 10, 10. There is also a transversely disposed angle iron 11 bolted to the front side of the legs 1 and arranged intermediate the angle irons 10. The vertically disposed flange of the angle iron 11 fits against the front side of the legs 1 and is bolted thereto by the bolts 12 and the horizontally disposed flange of said angle iron 11 is suitably notched to receive the legs 1.

There is a sign frame composed of the transversely disposed upper and lower side members 13, 13 preferably of wood and to the rear sides of which are secured the upper and lower retaining cleats 14, 14 whose lower and upper edges extend beyond the corresponding members 13. Suitable upper and lower moulding strips 15, 15 are secured to the inner side of the respective upper and lower side member 13 by means of the suitable dowel pins 16. There are the end members 17, 17 with the corresponding inside moulding strips 18, 18 secured thereto, in the manner above stated and the said side members and end members and their corresponding moulding strips are mitered together as shown in Figure 1. The moulding strips 15 are spaced inwardly from the cor-

responding retaining cleats 14 and the signboard 19 is inserted between them as shown in Figure 3. This signboard is preferably formed of sheet metal suitably secured to the

5 front side of a skeleton framework 20.

In erection, the framework structure, including the end A-frames are erected and the braces 3, 4 and cross braces 9, 10 and 11 are secured in place. The upper and lower side

10 members 13 may be then secured to the framework by the upper and lower bolts 5, 5'. The signboard 19 secured to its frame 20 is then positioned in place and the upper and lower moulding 15, 15 then secured to the upper

15 and lower side members 13 by means of the dowels 16.

Suitable brackets 21 are fastened to the signboard frame 20 and are engaged over the vertical flange of the angle iron 11 to form

20 an additional anchorage and support for the frame 20 to the framework structure. The end members 17 may then be nailed, at their ends, to the corresponding side members 13

25 and the moulding 18 then secured in place,

which will complete the structure. If it be desired to remove the signboard and signboard frame the bolts 5, 5' may be loosened and removed and the dowels 16 withdrawn and the signboard and its frame

30 may be then removed from the supporting structure without injury thereto and may be readily reerected for reuse without injury to, or destruction of, any of the parts.

What I claim is:

35 A structure of the character described including a frame like support having vertical supporting legs and including transversely arranged upper and lower angle irons and an intermediate angle iron secured to said

40 legs, said intermediate angle iron having a horizontal flange, notched to receive said legs, and a vertically disposed flange, a sign frame on said support formed of transversely disposed upper and lower side members having

45 upper and lower transverse retaining cleats associated therewith whose lower and upper edges extend beyond the corresponding side members, upper and lower moulding strips secured to the inner sides of the upper and

50 lower side members, end members and inside moulding strips secured thereto said end members being suitably secured to the side members, the moulding strips being spaced inwardly from said cleats, a sign board inserted between said cleats and moulding strips and being supported in the rear by angle iron brackets fastened to the rear of the sign board and engaged over the vertical flange of said intermediate angle iron.

60 In testimony whereof I have signed my name to this specification.

PIERRE L. MICHAEL
